US0D1108952S

(12) **United States Design Patent** (10) Patent No.: **US D1,108,952 S**
(45) Date of Patent: ** Jan. 13, 2026

(54) **BINDING ELEMENT**

(71) Applicants: **Piotr Konopka**, Bialystok (PL);
Krzysztof Czyszki, Bialystok (PL)

(72) Inventors: **Piotr Konopka**, Bialystok (PL);
Krzysztof Czyszki, Bialystok (PL)

(**) Term: **15 Years**

(21) Appl. No.: **35/524,010**

(22) Filed: **Jan. 29, 2025**

(80) **Hague Agreement Data**

Int. Filing Date: **Jan. 29, 2025**

Int. Reg. No.: **DM/244003**

Int. Reg. Date: **Jan. 29, 2025**

Int. Reg. Pub. Date: **Feb. 14, 2025**

(51) **LOC (15) Cl.** **08-08**

(52) **U.S. Cl.**

USPC **D8/386**

(58) **Field of Classification Search**

USPC D8/349, 352, 353, 354, 382, 499, 386

CPC F16B 13/061; F16B 37/04

See application file for complete search history.
